UNITED STATES PATENT OFFICE.

HERBERT E. WHITE, OF YOUNGSTOWN, OHIO, ASSIGNOR TO GENERAL FIREPROOFING COMPANY, A CORPORATION OF OHIO.

FEED MECHANISM FOR EXPANDED-METAL MACHINES.

1,205,299.

Specification of Letters Patent. Patented Nov. 21, 1916.

Application filed July 22, 1915. Serial No. 41,298.

To all whom it may concern:

Be it known that I, HERBERT E. WHITE, a citizen of the United States, residing at Youngstown, in the county of Mahoning and State of Ohio, have invented certain new and useful Improvements in Feed Mechanism for Expanded-Metal Machines, of which the following is a specification.

This invention relates to machines for manufacturing expanded sheet metal, and particularly to an improved feeding mechanism possessing special utility in its application to a die-press for developing expanded sheet metal of the diamond mesh type.

To this end, a primary object of the invention is to provide a press-feed or feed mechanism embodying means for rapidly and accurately handling a troughed expanded metal shape without imposing undue or excessive strain on any part thereof, or without interference with its proper movement between the dies of the press. In this connection, the invention also has in view the proper synchronizing of the improved feed mechanism with the action of the die-press so that there is uniformity and accuracy of operation at every movement of the sheet, and the necessary intermittent step-by-step movement of the latter performed positively and reliably.

Another object of the invention resides in the provision of a construction wherein the delivery set of feed mechanism is of a novel formation in order to provide for interlocking with the troughed expanded section of the fabric in a manner that will afford a positive feeding and delivery engagement therewith, so that when a sheet leaves the primary feeding set, its intermittent feed is positively and accurately taken up by the delivery feeding set.

With these and other objects in view, which will more readily appear to, and be understood by, those familiar with this art, the invention consists in the novel construction, combination, and arrangement of parts hereinafter more fully described, illustrated, and claimed.

While the improvements involved in carrying out the present invention are susceptible of structural modification within the scope of the appended claims, a preferred and practical embodiment thereof is

shown in the accompanying drawings, in which—

Figure 1 is a top plan view of a feed mechanism for expanding machines, embodying the present invention, and illustrating diagrammatically by dotted lines the preferable position and arrangement of the cutting and expanding dies of the press with which the said mechanism is correlated. Fig. 2 is a side elevation of the feed mechanism forming the subject of the present invention. Fig. 3 is an enlarged longitudinal sectional view of the delivery set of the feed mechanism, showing the progressive stepped setting of the successive rolls, and illustrating diagrammatically the crown portion of the troughed expanded fabric which passes between and is engaged by the drawing disks of the roll units; said view also accentuating the locations of the tie pieces or uncut portions of the fabric which are engaged by the projections of the drawing disks. Fig. 4 is an end elevation of one of the delivery roll sets, showing diagrammatically the cross sectional form of the troughed fabric as it appears in the roll pass. Fig. 5 is a detail elevation of one of the pawl and ratchet devices of the operating means for the roll sets. Fig. 6 is a detail sectional view on the line 6—6 of Fig. 1, through a pair of the rollers of the primary feeding set. Fig. 7 is a detail plan view of the troughed fabric. Fig. 8 is an enlarged detail view of the crown portion of the troughed fabric illustrating more clearly the relation of the tie pieces or uncut portions thereof to the gripping projections of the drawing disks.

Similar reference characters designate corresponding parts throughout the several figures of the drawings.

As indicated, the novel feed mechanism claimed herein is specially applicable to a die-press containing dies for developing a metal sheet from the blank into an expanded fabric or shape comprising a continuous series of troughed expanded sections having open meshes of a substantially diamond form.

In order that the construction and operation of the feed mechanism may be thoroughly understood, reference will first be made to the structural characteristics of the expanded metal shape referred to.

For purposes of illustration, it may be explained that the slitting and expanding operations necessary to produce an expanded troughed fabric of the character referred to, 5 may be and are successfully performed by the action of the slitting and expanding dies preferably of the character disclosed in my former Patent No. 1,049,632, dated January 7, 1913. These dies are operated within a 10 suitable press, diagrammatically indicated in the drawings and designated by the reference letter P. It will therefore be understood that the term "die-press" or "press" as employed herein will include a press containing 15 dies capable of producing the troughed expanded shape which is handled by the delivery roll units, as hereinafter more particularly pointed out. However, in this connection it may be further noted that 20 in Fig. 1 of the drawings, the location and arrangement of the individual die elements of the slitting and expanding dies are indicated diagrammatically by dotted lines. The effect of dies arranged in this manner, 25 as fully explained in the patent referred to, is to slit the sheet, and at the same time deform the slit areas into a series of adjoining troughed expanded sections a (see Fig. 4). It is this shape of material that is 30 developed by the die-press as the blank is received from the primary feeding set, and it is this shape of material that is engaged and delivered by the delivery feeding set.

Referring now to the features of the present invention, it will be noted that the primary feeding set essentially consists of a pair of superposed feeding rolls A and B. Preferably each of these rolls A and B includes a plurality of flat-faced friction feeding-rollers 1 carried by the transverse shafts 2 and 3 of the upper and lower rolls A and B respectively, the said shafts having their opposite ends journaled in the bearing members 4 and 5 of the framework of the machine. With this arrangement, the feeding rolls A and B are adapted to receive a blank metal sheet from the feed table 6 and frictionally clamp and engage the same therebetween to feed the press P. While the said shafts 2 and 3 are journaled in the bearing members above mentioned, they preferably project to one side of the member 5 as will be clear from Fig. 1, to receive the gear wheels 7 and 8, and it will also be noted that the shaft 3 in addition to having the gear 8 carries a ratchet wheel 9. Thus, as the gears 7 and 8 intermesh, it is obvious that the rolls A and B will be given an interrupted rotary feed movement when the shaft 3 is rotated intermittently by the ratchet wheel 9, as will hereinafter more fully appear.

A distinctive feature of the present invention resides in the construction and action of the delivery feeding set arranged at the discharging side of the press to receive the

troughed expanded metal shape. This delivery feeding set comprises a plurality of roll units 10, 11, and 12, which may be multiplied to any desired or required extent, and are preferably of duplicate construction. Upon an inspection of Figs. 3 and 4, it will be seen that each of these delivery roll units 10, 11 and 12 includes a pair of superposed feed rolls C and D, and each of these rolls in turn is preferably composed of a plurality of drawing-disks 13, of double tapered form. These disks 13 taper into a relatively thin or narrow peripheral edge of a toothed or corrugated formation made up of uniform and regularly alternating notches 14 and the gripping projections or teeth 14. With further reference to the structural features of the delivery feed rolls C and D of each unit, it will be observed more especially from Fig. 3, that the said drawing-disks 13 are arranged in side by side relation upon suitable shafts 15 disposed transversely of the framework at the delivery side of the press, and have suitable bearings in the opposite journal members 16 and 17. Thus, 90 the assembled feed rolls C and D of each delivery roll unit, present regularly alternating ridges and valleys which conform to the folded or troughed formation of the expanded metal fabric or shape as it comes from the die-press P. This will be clear from an inspection of Fig. 4, wherein the corrugated or toothed peripheries of the drawing-disks 13 of the superposed rolls C and D are shown in vertical alinement so 95 that the troughed expanded metal shape emerging from the die-press will have the sinuous crowns or apices of its troughs engaged between the drawing-disks 13 comprising the superposed feed rolls C and D of each of the delivery units 10, 11 and 12. See also Figs. 3 and 8.

A novel and practical feature of the invention resides in the special relation of the several delivery roll units 10, 11 and 12. This feature preferably involves having the number of roll units equal to the relation existing between the length of a half diamond mesh and the length of an uncut portion of the strands between adjacent diamonds. For instance, if the length of a half diamond mesh is three times the length of the uncut portion or "tie," three sets of rolls should be used, as shown in the drawings. It is also preferable to provide and maintain a progressively stepped setting of the successive roll units, that is to say, the drawing disks 13 of each succeeding delivery roll unit are set with their gripping projections spaced a proportional angular distance from the set positions of the similar projections of the preceding roll unit, and therefore in stepped relation thereto. Accordingly, only one roll unit at a time grasps uncut portions of the strands, so that the positive drawing action 130

in the delivery set is successively picked up by the succeeding roll units. As the troughed expanded shape leaves the dies of the press, the first roll unit 10 grasps uncut portions of the strands and exerts a drawing action upon the material, and this same action is progressively taken up by the drawing disks of the succeeding roll units. And, it will be noted that during the time the troughed fabric is within the passes of all of the delivery roll units, the disks of the first unit will grip uncut portions of the strands, while the disks of the next roll units are in a disengaged position, but ready to grip uncut strands as the grip of the first rolls is released, and so on throughout the entire series of delivery roll units, according to whatever number of said units are employed. In this connection, it will be further noted that the novel relation of the gripping projections can best be arranged when the distance between the centers of the roll units is not equal to a multiple of the half diamond length, or, in other words, the spacing between the roll units in the delivery set should be either more or less than a multiple of the length of a half diamond strand. By reason of thus carefully calculating the relative distances between the various parts of the delivery roll units, in their relation to the diamond mesh fabric, certainty and reliability of operation are attained, and these are necessary in order to properly and successfully handle the expanded metal fabric having the peculiar characteristics of the troughed expanded shape referred to.

Any suitable operating mechanism may be employed for operating the rolls of the feeding and delivery sets, but for purposes of illustration a practical construction is shown in the drawings. Referring thereto, it will be seen that the feed rolls C of the several delivery roll units are provided at one end with suitable gears 18 which intermesh with corresponding gears 19 carried by the ends of the shafts 15 of the lower feed rolls D. In connection with the shafts 15 of the lower rolls D in the units 10 and 12, it will be noted that the same are provided with driving pinions 20 which are adjacent to the gears 19. For the purpose of obtaining a uniform feed of all of the delivery rolls in each unit, there are also provided suitable reversing pinions 21 which intermesh with the pinions 20 of the units 10 and 12, and in turn mesh with a driven pinion 22 carried by the shaft 15 of the roll D in the intermediate delivery roll unit 11. Accordingly, it will be apparent that the said shaft 15 of the roll D in the intermediate delivery roll unit 11 transmits power to each of the rolls C and D of all of the delivery roll units, and to this end this same shaft 15 also carries rigid therewith a ratchet wheel 23 which, like the ratchet

wheel 9 on the shaft 3, forms a part of the pawl and ratchet mechanism for securing the necessary intermittent feed movement for the metal sheet.

The pawl and ratchet mechanism employed for the above purpose is preferably duplicated for both the primary feeding set A-B, and the delivery roll unit 11. That is to say, in each case the device includes a swinging pawl carrier 24 which is loosely mounted on the shaft 15 of the roll D in the case of the delivery roll unit 11, and on the shaft 3 of the primary feeding set A-B. At the upper end of the pawl carrier 24, is a pivoted pawl 25 which is held in engagement with the teeth of the ratchet wheels 9 and 23 respectively by means of a spring 26 carried by a spring abutment 27 rigid with the body of the swinging pawl carrier 24. The lower end of the pawl carrier at the delivery roll end of the machine is pivotally connected as at 28 with a connecting rod 29, which in turn is pivotally attached, as at 30, with the pawl carrier of the entering feed roll set, as clearly shown in Fig. 2.

The connecting rod 29 is coupled at one end, as at 31, to an operating bell crank 32 journaled to the framework of the machine, as at 33, and having a suitable connection 34 with a prime actuating rod 35. Thus, it will be apparent that as the said prime actuating rod 35 operates the bell crank 32, the latter will impart a reciprocating motion to the connecting rod 29, which will in turn rock the swinging pawl carriers 24 respectively mounted on the shafts 3 and 15. As these pawl carriers 24 rock loosely on the shafts, it will be apparent that the pawl 25 on each carrier will engage with the ratchet wheels 9 and 23 to thus impart an intermittent rotary motion in the same direction to both the primary feeding set and the delivery feeding units 10, 11 and 12. It will also be apparent that because of the construction and arrangement above described, a uniform intermittent motion in the same direction is imparted to all of the individual rolls A-B and C-D of both the feeding and delivery sets, thereby insuring a positive and intermittent entrance of the sheet into the dies of the press P, and also a corresponding intermittent drawing of the same as it emerges from the said press in its troughed expanded form in the manner herein explained and pointed out.

The operating mechanism illustrated in the drawings has been described with particularity for the purpose of making the operation of the invention entirely plain, but as indicated, any equivalent means may be employed to simultaneously operate the feeding and delivery sets intermittently without departing from the invention, and it will be understood that changes in the form, proportion, and minor details of con-

struction may be resorted to without departing from the spirit or sacrificing any of the advantages of the invention.

I claim:

- 5 1. In a feed mechanism for metal expanding machines, a plurality of similar roll-pairs having gripping projections arranged to progressively and successively engage different tie pieces of the fabric, and means for
10 operating all of the roll-pairs at equal speed.
2. In a feed mechanism for metal expanding machines, a plurality of equal-diameter roll-pairs provided with gripping elements having a progressive angular relation, means for maintaining said relative position of the several rolls, and means for driving all of the roll-pairs at equal speed.
3. In a feed mechanism for metal expanding machines, a plurality of similar roll-pairs having gripping elements progressively displaced angularly, and driving means for operating all of the roll-pairs at equal speed.
4. In a feed mechanism for metal expanding machines, a plurality of similar roll-pairs having gripping projections, the gripping projections of the several pairs of rolls having a progressive angular displacement from the plane of the vertical diameter of the rolls, and driving means for operating all of the roll-pairs at equal speed.
5. In a feed mechanism for metal expanding machines, a plurality of similar roll-pairs each consisting of spaced drawing disks provided with gripping elements, the gripping elements of successive rolls having a progressive angular setting, and driving means for operating all of the rolls at equal speed.
- 40 6. In a feed mechanism for metal expanding machines, a plurality of similar roll-pairs consisting of spaced drawing disks

having peripheral gripping projections, with the gripping projections of one pair being spaced a proportional angular distance from 45 the set positions of those in an adjacent pair, and driving means for all of the rolls.

7. In a feed mechanism for metal expanding machines, a plurality of roll-pairs having corrugated peripheries consisting of uniform regularly alternating projections and notches, the projections for the disks of one roll having a progressive angular setting with relation to those of the disks of the preceding roll-pair, and driving means for 55 operating all of the rolls at equal speed.

8. In a feed mechanism for metal expanding machines, a plurality of roll-pairs consisting of double tapered spaced driving disks having corrugated peripheral edges, 60 the corrugated edges of the disks of one roll-pair having a progressive angular setting with relation to the corrugated edges of the disks of the preceding roll-pair, and driving means for operating all of the rolls at equal 65 speed.

9. In a feed mechanism for metal expanding machines, the combination with a press having means for forming an expanded troughed metal shape, of a primary feeding 70 set for the press, a delivery feeding set for the press including a plurality of similar roll-pairs having peripheral gripping projections for progressively and successively engaging different tie pieces of the fabric, 75 and driving means for simultaneously operating both feeding sets intermittently.

In testimony whereof I hereunto affix my signature in the presence of two witnesses.

HERBERT E. WHITE.
